UNITED STATES PATENT OFFICE

FRED INMAN SMITH, JR., OF PLAINFIELD, NEW JERSEY

AUTOMATIC WINDOW-SAFETY LATCH

Application filed October 27, 1924. Serial No. 745,957.

This invention relates to devices for preventing the opening of windows from the outside, and applies particularly to the vertical-moving double-sash windows, with one or both of the sashes normally operable. Among the objects are to produce a safety device which will automatically function to latch the movable sash, or interlock both movable sashes, when the window is closed or when partially closed to the desired position, and while providing an automatically setting device to embody therewith adjustability, also to provide such devices with assured efficiency, capable of cheap production, simplicity and durability, and, in general, to meet various requirements that provide for safety and the fulfillment of the services required of such an article.

It is known that devices are in general use which lock two sashes, when a window is closed, but which must be set after closing the window, and various devices for locking sashes may either not function reliably, many can be manipulated from the outside of the window for unauthorized ingress, others lock only when the window is completely closed providing no means of locking when partially closed, while others cause wear and damage becoming inefficient or useless after short use, and, in general, window safety devices have had one or more defects, and do not meet all of the requirements which are met by the invention herein set forth. This invention also provides for a construction of safety device which may be made in a single or limited number of sizes, and adjustable or adaptable to all sizes of windows, and by its simplicity avoids the use of mechanism liable to derangement of wear, and, in all, aims to produce an article of manufacture which once installed will most effectually meet all requirements and be as durable as the other permanent parts of the window structure.

Particular embodiments of my invention are shown in the accompanying drawings, in which:

Fig. 1 is an elevation showing one form of the device in position latching a window, and dotted in position permitting the opening of a window.

Fig. 2 is a cross-section of window end, side view of latching device.

Fig. 3 is a fragmentary cross-section on enlarged scale, on line 3—3, Fig. 1.

Fig. 4 is a fragmentary cross-section on enlarged scale, on line 4—4, Fig. 1.

Fig. 5 is a side view on enlarged scale of the foot or lower end of the latching bar.

Fig. 6 is a perspective of the upper member and attaching plate.

Fig. 7 is a perspective of the lower extension member.

Fig. 8 is a perspective view of the assembled device with parts in modified form.

Fig. 9 is a fragmentary view in section on larger scale, on line 9—9, Fig. 8.

Fig. 10 is a fragmentary view in section, on line 10—10, Fig. 8.

Fig. 11 is a cross-section on line 11—11, Fig. 8, on larger scale.

These embodiments of the invention are illustrated with the window casing A, with the upper window sash B and the lower window sash C, with the upper sash frame b and vertical frame b', and the lower sash top frame c and side frame c'. Assembled for use on the window, the latching bar comprises the pivot bar 1 and the adjustable bar member 2. The pivot bar swings on the pin 4 supported on the plate 3 rigidly secured to the sash frame at the junction of b and b'. The adjustable bar member 2 has a foot 2', a slot 5 and a wing nut 6 on the bolt 7 passing through the slot and attached to the swinging bar member 1. A claw 8 on the upper end of the adjustable or extension member 2, is adapted to engage any one of a plurality of perforations 9 or recesses, in the swinging bar 1. The foot 2' at the lower end of extension member 2 provides a base for engagement with the top surface of sash frame c, with the lower surface 2'' preferably inclined, so that the reaction in compression of the latching bar, will tend to bend the entire bar against the upper sash side frame member b'. This slight inclination of the lower surface of the foot 4 is shown at an exaggerated angle for the purpose of illustration in Fig. 5. On one edge of the foot a roller 10 is supported by the pin 11 on the end of the adjustable bar 100

2 and adjacent the foot 2', but slightly above the extremity of the foot surface 2'', so that roller will not engage the top of the sash frame *c* when the latching bar is in its locking position. The roller is so arranged that when the latching bar is swung out of locking position, as, for example, illustrated in dotted lines, Fig. 1, the roller 10 will engage the top surface of the sash frame *c* so that the act of opening, that is, raising the lower sash *C* will automatically swing the latching bar, with the roller 10 sliding easily on the top of the sash frame, and thereby offer no resistance to raising the lower sash to the top of the window, barring only the short space occupied by the width of the latching bar when in horizontal position from its pivot 4.

The two members 1 and 2, thus provide an adjustable latching bar with predetermined lengths of adjustment, at which the end claw or stud 8 engages firmly to resist compression of the bar or mutual sliding of the two members, and the wing nut 6 provides for clamping the two members solidly together in the desired position of adjustment for length. The adjustment for length may be to provide that one size of latching bar may be used for different sizes of window sashes, and also the adjustment provides for setting the length to resist opening of the lower sash beyond a predetermined short distance. In this way the latching bar may be used to firmly latch the upper and lower sash against relative movement with the window completely closed, or a limited extent of adjustment provides for leaving the lower sash open a short distance and still latched against any further movement which would permit unauthorized ingress from the outside of the window.

The further advantages will be understood from the modified form as shown in the other figures, in which the pivot bar 12 and the extension bar 13 are formed of through cross-section, and nesting together in such a way that when clamped tight together the slope of the trough sides provides for a tight engagement and a binding in order to stiffen the bar when latching is set for any predetermined length of adjustment. Various forms of cross-section may be used in order to stiffen the bar as a strut to resist compression strains due to any attempt to raise either of the sashes, and advantages of stiffness and security of clamping between the surfaces of the two bars may be realized in various ways, while the particular form herein described serves to illustrate particular factors of advantage, which may be, however, variously attained.

In the modified form the bar 12 is pivoted to the upper sash plate 14 with pivot 15, and when in vertical position this bar is limited against swinging in one direction by the stop 16, thereby preventing it from knocking against the window casement parts when it

swings into locking position upon lowering or raising sashes to close the window. Such stop may be otherwise provided, but is preferably an embodiment with the regular parts of the device to avoid any necessity of adding an extra part for adjustment to the window. The slot 17 in the adjustable section of the bar 13 is adapted to permit longitudinal adjustment with the clamping pin 18 screwed into or riveted to the pivot bar 12 passing through the slot, and in this form of clamp a pin 19 supports an eccentric latch 20 having a cam surface 21 and a thumb pressed end 22 formed to readily permit setting the clamp, as well as releasing it, while the eccentricity of the clamping surface 21 assures a hold-fast position, when the thumb pressed end 22 is pressed down against the adjustable plate 13, as shown in Figs. 8 and 10. The lower end of such through section member 20 may have the sides cut away and part of the end turned at substantially right angles to form the foot 23, while another portion of the end is bent to provide engagement for the pin 24 to carry the roller 25, similar in arrangement to the roller on the form shown in Fig. 7. At the upper end of the adjustable bar member, a pin or lug 26 is secured in a manner adapted to register with the series of holes 27-27 in the pivot bar 12, for adjustment as to length, and a corner 28 of the pin 26 may be beveled to assure the engagement with the desired hole and still leave a straight and square engagement in the direction of thrust, between said stud and the other side of the hole for adjustment. The trough section shown provides a sufficient flat base to accommodate suitable clamping means, but the cross-section may also be V shape or channel section in some cases where the window dimensions are sufficient to accommodate the size of material required when so constructed.

It will be seen that the particular arrangement of foot with a slightly inclined lower surface causes the tendency of the bars, as a whole, to bend in the direction which you press it against the side frame of the sash, thereby assuring resistance to compression, and under excessive strain the outer edge of the foot surface being sharp, would be forced into the wood of the sash and prevent it from slipping out of its locking position.

In any of the forms herein described, it will be seen that a window safety-latch is provided which may be attached rigidly for functioning, as by securing the pivot plate to the upper sash frame in a position to avoid any interference with the normal operation of the window. It provides for attaching means which will not interfere with any reasonable movement of the lower or upper sashes for opening. When opening the window from the inside a slight swing of the latching bar out of its vertical position permits the movement of the lower sash, which,

upon engagement with the foot of the bar, readily moves the bar on its pivot without any resistance in the unlatched position.

When a window is closed, the bar automatically lowers itself and finally drops into the latched position, so that unconsciously to the operator the window is latched against unauthorized ingress, with all of the locking parts out of position where tampering from the outside is impossible, except through breaking or destruction of the window.

The construction is simple and cheap, and may be attached in a simple manner without injury to the sash, and engaging only substantial parts of the sash well adapted to resist any attempt at opening and the resultant compression or strains on the latching bar. Ready adjustment is provided, for example, to permit latching the window in warm weather so that if raised a few inches it cannot be moved further without access from the inside. As an article of manufacture, furthermore, it can be made of light material and still capable of resisting all strains involved, so that it is economical for transportation and distribution. When in operation its location and compactness avoid interference with any normal manipulation of the window or adjacent parts.

Conditions of manufacture and design for different sizes or finish, may be accommodated by variations in dimension, form and arrangement, without departing from the spirit of my invention, but what I claim and desire to secure by Letters Patent is:

1. A window-latching bar comprising an adjustable strut member, a pivotal connection at the upper end secured adjacent the upper part of a window, a thrust foot formed integrally with the lower end, and anti-friction means on said foot adapted to engage an upper surface portion of the lower sash after the bar has been swung partially out of its vertical position.

2. An article of manufacture, a window-latching bar comprising two members together providing for the extension of the bar and joint fixed securing of the two members for predetermined lengths of strut, a thrust-resisting pin interengaging the two members, and manual clamping means to clamp the two members rigidly together in adjusted position, and a foot at one end for engagement solely by pressure against a flat surface on one window member and having a surface substantially at right angles to the axis.

3. A window-latching device including a strut, means at either end thereof for attachment respectively to one sash and to automatically engage the other sash, said attachment means on the first sash resisting by compression the strain of attempted opening of said window and providing for means to cause the strut to press against the first sash when compression springs the strut laterally.

4. An automatic window-latching device including a compression strut stiff from end-to-end, means of attachment thereof to a window sash remote from any sash joint accessible from the outside, and means whereby the strut assumes a locking position automatically on the closing of the window.

5. A window-latching device comprising means for preventing relative movement of two relatively sliding sash members, said means including a bar rigid from end to end adapted to swing as a rigid bar in a plane parallel to the window pane on a pivot attached to the upper part of the upper sash, and a foot on said means adapted to form a free contact pressure engagement with a horizontal surface on the lower sash when said means is in a substantially vertical position parallel with the plane of motion of the sashes.

In testimony whereof, I have signed my name to this application, this 18th day of October, 1924.
